UNITED STATES PATENT OFFICE.

ALFRED HENRY GREBE, OF HOLLIS, NEW YORK.

DESIGN FOR A CABINET FOR RADIO APPARATUS.

Application filed December 5, 1924. Serial No. 11,597. Term of patent 7 years.

To all whom it may concern:

Be it known that I, ALFRED HENRY GREBE, a citizen of the United States, residing at Hollis, in the county of Queens and State of New York, have invented a new, original, and ornamental Design for Cabinet for Radio Apparatus, of which the following is a specification, reference being had to the accompanying drawing, forming part thereof, in which,

Fig. 1 is a view in front elevation of a

cabinet for radio apparatus, showing the complete assembly of my design elements;

Fig. 2 is an end view thereof;

Fig. 3 is a detail view of the main dial escutcheon; and

Fig. 4 is a similar view of the vernier escutcheon.

I claim the ornamental design for a cabinet for radio apparatus, as shown.

ALFRED HENRY GREBE.
